DETACHABLE RELAY

Charles P. West, Forest Hills, Pa., Roy M. Smith, Livingston, N. J., and William A. Lewis, Jr., Ithaca, N. Y., assignors to Westinghouse Electric & Manufacturing Company, East Pittsburgh, Pa., a corporation of Pennsylvania

Application March 23, 1939, Serial No. 263,722

11 Claims. (Cl. 175—294)

Our invention relates to detachable instruments, and it has particular reference to means for preventing incorrect operation of detachable instruments during attachment and removal thereof.

Because of the facility with which detachable instruments may be removed, serviced, adjusted and replaced, a detachable construction is highly desirable for relays and similar instruments. When employed for sensitive relays such a construction may result in incorrect operation of the relay during attachment and removal thereof because of the tendency of these relays to close their contacts under the vibration incident to such removal or attachment. The incorrect operation of the relay would result in improper actuation of the circuit breaker or other equipment controlled thereby, and such improper operation is highly objectionable.

In accordance with our invention, incorrect operation of a detachable relay or other detachable instrument is prevented by including in the control circuit thereof a switch or other control element which must be actuated before the detachable relay or instrument can be removed and replaced. Because the relay contacts or other control means of the detachable instrument are rendered ineffective, the instrument may be handled as desired without fear of incorrect operation thereof. For relays energized from current transformers, we also provide circuit completing means for short circuiting the current transformers prior to removal of the instruments.

It is, therefore, an object of our invention to render the control means of a detachable instrument ineffective prior to removal thereof.

It is another object of our invention to provide a relay having a control circuit with means for opening said circuit prior to removal of the detachable relay.

It is still another object of our invention to provide a detachable instrument with fastening means and a control element responsive to the condition of the fastening means.

It is a still further object of our invention to provide a detachable relay having means for rendering the relay contacts of a relay energized from a current transformer ineffective prior to removal of the relay from its base and having circuit completing means for short circuiting the current transformer.

Further objects of our invention will be apparent from the following description taken in conjunction with the accompanying drawings, in which:

Figure 1 is a diagrammatic view of an electrical circuit embodying our invention;

Fig. 2 is a view in side elevation with parts broken away of a detachable relay suitable for use in the circuit of Fig. 1;

Fig. 3 is a view in side elevation with parts broken away of a modification of the relay shown in Fig. 2;

Fig. 3a is a detail view in side elevation with parts broken away of a further modification of the relays shown in Figs. 2 and 3.

Fig. 4 is a view in side elevation of a switchboard relay embodying our invention;

Fig. 5 is a view in side elevation with parts broken away of a modification of the structure shown in Fig. 4;

Fig. 6 is a detail view in section of a further modification of the structure shown in Fig. 4;

Fig. 7 is a fragmentary view in front elevation of the relay structure shown in Fig. 6; and

Fig. 8 is a diagrammatic view of an electrical circuit embodying a modified control designed in accordance with our invention.

Referring to the drawings, Fig. 1 shows one conductor 1 of an electrical circuit to be protected. Protection of this circuit is effected by means of a circuit breaker 2 having a solenoid control 3 for tripping purposes. Actuation of the circuit breaker is effected by means of a relay 4 which has an operating coil 5 actuated from the conductor 1 through a current transformer 6. The relay 4 also includes a pair of contacts 7 which are included in a local circuit breaker tripping circuit comprising a battery 8 and a trip coil 9. The specific relay illustrated is of the overcurrent type.

As the current flowing through the conductor 1 increases, it reaches a value sufficient to actuate the contacts 7 thereby completing a circuit for the trip coil 9 and tripping the circuit breaker 2. If the relay 4 is of a detachable construction, attachment and removal thereof invariably are accompanied by some vibration of the instrument. Such vibration in the case of a sensitive relay may be sufficient to actuate the contacts 7 to their closed position, thereby incorrectly tripping the circuit breaker 2. In order to prevent incorrect operation, it is possible to include in the local circuit a switch 10 which is connected to the trip coil 9 and the contacts 7, respectively, by conductors 11 and 12. By opening the switch 10 prior to removal of the relay, the condition of the contacts 7 has no further effect upon the actuation of the circuit breaker 2, and the relay 4 may be handled as desired.

Manual operation of the switch 10 is disadvantageous for the reason that it may not be operated because of carelessness or oversight on the part of the operator. For this reason, it is desirable to so interlock the switch 10 with the detachable relay that it must be operated before the relay can be detached from its socket. A relay embodying this interlocking desideratum is illustrated in Fig. 2.

In Fig. 2 the relay is contained in a housing 13 which is provided with a plurality of detachable contact blades 14, 14a. These contact blades are detachably received in contact jaws 15, 15a carried on insulating blocks 16 which are mounted in a socket 17. Removal and replacement of the relay are effected by merely lifting the housing 13 and the contact blades carried thereby from the socket and replacing it after desired inspection and adjustments have been carried out. The socket may be provided with an opening 17' for receiving a conduit for wiring purposes.

In order to secure the relay in place, the housing 13 and the socket 17 are provided, respectively, with flanges 18 and 19 which abut each other when the relay is in mounted position. For securing the various parts together, a sealing ring 20 embraces the flanges 18 and 19 and is attached in place by a bolt 21 which passes through suitable clip retaining means 22 on the ring 20. The various parts of the detachable relay structure thus far described may be patterned after the detachable construction for watthour meters disclosed in the Bradshaw et al. patent No. 1,969,499, assigned to the Westinghouse Electric & Manufacturing Company.

As illustrated in Fig. 2, the switch 10 is positioned within the socket 17 and comprises a pair of contacts mounted on spring arms 23 and 24. When free, these arms are in the positions depicted by the dotted lines, and the switch consequently is open. Closure of the switch is effected by means of an insulating push rod 25 which slidably passes through a boss 26 formed in the socket 17. The push rod 25 is positioned to engage the clip means 22 when the latter is in its attached position.

In its attached position, the clip means 22 depresses the push rod 25 to close the switch 10. When the relay is to be detached from its socket, the first step is to remove the sealing ring 20. The removal of the sealing ring, in turn, releases the push rod 25, and the switch 10 consequently is placed in its open condition because of the resiliency of the arm 24. With the switch in open position, the relay may be removed from the socket without fear of incorrect operation of the circuit breaker 2. As apparent from Fig. 2, the arm 24 of the switch is connected to the relay contacts through the conductor 12, the contact jaw 15 and the contact blade 14 appearing to the left in Fig. 2.

It will be noted from Fig. 1 that the relay operating coil 5 is connected to a current transformer 6. When the relay 4 is removed from its socket, unless some provision were made, the current transformer secondary would be open and dangerously high voltages would be produced therein. For this reason, we prefer to provide the relay structure with a short-circuiting switch for the current transformer secondary. The position of this switch 27 is illustrated diagrammatically in Fig. 1. A specific construction for the switch is shown to the right in Fig. 2. As will be apparent from the illustration, the switch 27 consists of a spring conductive leaf which nor-

mally is biased in contact with the contact jaw 15a. When the contact blade 14a is inserted in the contact jaw, the resultant movement of the contact jaw is transmitted through an insulating push rod 28 which engages the inner end of one contact jaw convolution, passes through the outer portion of the same convolution of the contact jaw, and engages the resilient switch 27. An insulating block 29 may be provided for the remaining half of the contact jaw 15a to increase the range of movement of the push rod 28. With this construction, as the relay is removed from its socket, the switch 27 engages the side of the contact jaw 15a to short circuit the current transformer secondary, thereby preventing damage to the current transformer. A design suitable for the switch 27 is disclosed in the Bradshaw et al. Patent No. 2,096,479, assigned to the Westinghouse Electric & Manufacturing Company.

In the modification shown in Fig. 3, the switch 10 is replaced by a switch 10a which is actuated by means of a key 30. This key may be withdrawn from the switch only when the switch is in its open position. Conductors 11a and 12a correspond to the conductors 11 and 12 of Figs. 1 and 2. The relay 4 in Fig. 3 is retained in position by means of a lock 31 which has a bolt 32 engaging a lug 33 affixed to the relay. The lock 31 is actuated by the same key 30 employed for the switch 10a, and the key may be removed from the lock only when the bolt 32 is in its extended or locking position. Consequently, in order to remove the relay from its socket 17 the key 30 must be moved to open the switch 10a, this, of course, rendering the relay contacts ineffective. The key 30 then may be removed from the switch for insertion in the lock 31, and may be actuated to release the relay 4 from its socket. If desired, the switch 10a may be built into the lock 31 as shown in Fig. 3a so that rotation of the key in one direction opens the switch and retracts the bolt 32. The return of the key to its original position would reclose the switch and advance the bolt to its locking position.

Fig. 3a illustrates a socket construction similar to that of Fig. 3 except that the switch 10a and the lock 31 are replaced by a corresponding switch 100 and a corresponding lock 310. The switch 100 and the lock 310 are associated so that a single key 300 suffices to actuate both the switch and the lock. Rotation of the key in one direction operates to extend the bolt 320 of the lock and to close the contacts of the switch 100. Rotation of the key in the opposite direction operates to retract the bolt 320 and to open the contacts of the switch 100. Except for the substitution of a key for simultaneously operating both the lock and the switch Fig. 3a is similar to Fig. 3.

The relay constructions thus far described may be adapted either for individual mounting or for switchboard mounting. For switchboard mountings the socket 17 would be a part of the switchboard panel.

Another modification illustrated as mounted on a switchboard is shown in Fig. 4. In this figure, a relay 34 is attached to a switchboard panel 35 by one or more bolts 36. The relay 34 is provided with contact blades 37 which pass through openings in the switchboard and engage contact jaws 38 mounted on an insulating panel 39 positioned in the rear of the switchboard panel.

The construction of Fig. 4 is provided with a switch 10b and conductors 11b and 12b corresponding to the switch 10 and conductors 11 and

12 of Figs. 1 and 2. One of the contacts 40 of the switch 10b is mounted on an insulation block 41 attached to the switchboard panel 35. The remaining contact 42 is mounted on a lever 43 that is pivoted on a fulcrum 44 carried by the switchboard panel. Insulation 45 is interposed between the contact 42 and the lever 43. Movement of the lever is restricted by a pair of stops 46 and 47 which also are mounted on the switchboard panel. Normally the switch 10b is biased in its open position by means of a spring 48 when the relay 34 is detached from the switchboard panel. In order to close the switch 10b and place the relay 34 in operative condition, a bolt 49 is passed through a flange 50 formed on the relay into threaded engagement with the lever 43. Rotation of the screw 49 into attached position rotates the contact 42 into switch-closing position. It will be noted from Fig. 4 that the relay 34 cannot be removed from the switchboard panel until the bolt 49 has been removed. Removal of this bolt, of course, results in opening of the switch 10b, and this opening renders the relay contacts ineffective.

Referring to Fig. 5, a modification of the structure shown in Fig. 4 is illustrated, in which a relay 34a, a switchboard panel 35a, contact blades 37a, contact jaws 38a and a sub-panel 39a correspond, respectively, to the elements 34, 35, 37, 38 and 39 of Fig. 4.

In Fig. 5 a switch 10c for rendering the relay contacts ineffective comprises a contact 51 attached to the relay 34a and removable therewith, and a contact 52 which is carried by a lever 53 but insulated therefrom. A conductor 11c is employed for connecting the contact 52 to a circuit breaker trip coil and corresponds to the conductor 11 of Figs. 1 and 2. The lever 53 is pivoted on a fulcrum 54 which is attached to the sub-panel 39a and is restricted in movement by a pair of stops 55 and 56. Normally, the switch 10c is maintained in closed position by means of a spring 57. The condition of the switch 10c is controlled by a jackscrew 58 which has a shoulder 59 engaging a flange 50a on the relay and which is in threaded engagement with the lever 53. By suitable rotation of the jackscrew 58 the lever 53 is rotated in contact opening direction until it engages the stop 55. Continued rotation of the jackscrew 58 then is effective for forcing the relay 34a away from the contact jaws 38a and the switchboard panel 35a. The jackscrew 58 passes freely through the sub-panel 39a.

In many relay units, the number of contacts required is so large that the frictional engagement of contact blades with contact jaws makes removal and insertion of the relay difficult. For this purpose, the jackscrews 58 may be desirable for forcing the relay 34a from its mounted position against the resistance offered by the contact blades and jaws. If desired, one or more additional jackscrews 58a similar to the jackscrew 58, may be provided for applying removal force against other portions of the relay structure. Additional screws 60 may be provided for additionally securing the relay 34a to the switchboard panel 35a.

It should be noted that the lever 43 of Fig. 4 and the lever 53 of Fig. 5 move arcuately relative to the screws 49 and 58, respectively. For this purpose, the threaded engagement of each screw with its lever may be made slightly loose, or the required movement may be provided in any known way.

Fig. 6 includes a relay 34b, switchboard panel 75

35b, insulating sub-panel 39b, flange 50b and switch 10d which correspond, respectively, to the elements 34, 35, 37, 38 and 10b of Fig. 4. The switch 10d is actuated by means of a jackscrew 58b which is in threaded engagement with the sub-panel 39b. Two collars 65, 66 are provided on this screw for forcing the relay 34b into or away from its attached position. These collars engage opposite faces of the flange 50b through 10 which the intermediate portion of the jackscrew passes, the flange being provided with either a hole or a notch 67 for receiving the intermediate portion (see Fig. 7).

The switch 10d has two contacts 68, 69, the 15 stationary contact 68 being mounted on a post 70 which is attached to the sub-panel 39b. A pair of conductors 11d, 12d, which correspond to the conductors 11, 12 of Fig. 1 connect the contacts respectively to the relay trip coil and 20 trip contacts in the manner disclosed in Figs. 1 and 4.

Actuation of the switch 10d is effected through a lever 71 which is pivoted on a fulcrum 72 carried by the sub-panel. At one end, the lever carries an insulating block 73 on which one contact 69 is mounted. The opposite end of the lever is provided with an opening 74 for slidably receiving the jackscrew 58b. A switch actuating collar 75 is mounted on the jackscrew for engaging the lever 71 and moving the lever in contact closing direction when the jackscrew 58b is rotated to force the relay 34b into its attached position. When the jackscrew is rotated to release the relay 34b, a spring 76 moves the lever 71 into engagement with a stop 77 carried by the sub-panel. In this position of the lever the contacts 68, 69 are separated.

In the control systems of Figs. 5 and 6, it should be noted that the operation of the switch in each case takes place during a very small portion of the travel of the jackscrews. Consequently the remaining travel of each jackscrew is employed primarily for controlling the attachment or release of the relay from its supporting base.

Although in the relay installations thus far described the relay contacts normally are in open position and are closed for tripping circuit breakers, for some purposes it may be desired to employ relays having normally closed contacts which are opened for control purposes. For example, in Fig. 8 a relay 81 is energized from a circuit 82 in accordance with the voltage of the circuit. The relay is provided with a pair of contacts 83 which are maintained in a closed position as long as the voltage remains above a predetermined value. When the voltage of the circuit 82 falls below this predetermined value, the contacts 83 open for control purposes. If it is desired to protect such a relay from incorrect operation during detachment, a switch 84 may be connected across the relay contacts. This switch would be closed prior to removal of the relay in order to prevent inadvertent opening of the contacts 83 from affecting the control circuit.

The relays heretofore described may be modified readily to provide the sequence of operation called for in Fig. 6. For example, in Fig. 2, the switch 10 may be so positioned that the push rod 25 engages the arm 23, the arms 23 and 24 being formed to normally maintain the switch 10 in closed position. Depression of the push rod 25 then would tend to open the switch. Similarly, in Fig. 3 the switch 10a may be designed so

that the key 38 can be removed only when the switch is in closed position. Corresponding modifications may be made in the relay constructions illustrated in Figs. 4 and 5.

Although we have described our invention with respect to certain specific embodiments thereof, it is obvious that numerous modifications thereof are possible. Therefore, we do not wish our invention to be restricted except as required by the appended claims when interpreted in view of the prior art.

We claim as our invention:

1. In an instrument unit, a detachable electrical relay instrument having circuit controlling contact means subject to operation by shock, an instrument base for detachably receiving said instrument, a circuit controlled by said instrument, a switch means operable for changing the condition of said circuit, said switch means requiring actuation before said instrument can be moved substantially from its operative attached position on said base, and means electrically connecting said switch means to said circuit for controlling the effectiveness of said contact means.

2. In an instrument unit, a detachable electrical relay instrument having circuit controlling contact means, a base for detachably receiving said instrument, a lock for preventing removal of said instrument from said base, a switch, means connecting said switch in circuit with said contact means, and means responsive to the actuation and release of said lock for operating said switch to control the effectiveness of said contact means, said operating means including means for actuating and releasing said lock.

3. In a relay unit, a detachable relay having circuit controlling contact means subject to operation by shock, a base for detachably receiving said relay, a trip circuit controlled by said relay, a circuit interrupting device connected to said trip circuit for controlling the effectiveness of said relay on said trip circuit, and actuating means for said circuit interrupting device, said actuating means including means positioned in the path of travel of said relay relative to said base for assuring actuation of said circuit interrupting device to a predetermined position prior to substantial movement of said relay from its mounted position on said base.

4. In an instrument assembly, a detachable electrical relay instrument having circuit controlling contact means, supporting means for detachably supporting said instrument in an operative position, said detachable instrument and supporting means having cooperating detachable electrical contact means, means cooperating with said supporting means and instrument for forcing said detachable instrument towards and away from its operative position relative to said supporting means, second circuit controlling means responsive to the condition of said last-named means, and means connecting the contact means of said instrument and said second circuit controlling means in a circuit wherein the condition of said second circuit controlling means determines the effectiveness of the contact means of said instrument to control the circuit.

5. In an instrument unit, a detachable electrical relay instrument having circuit controlling means, a base for detachably receiving said instrument, securing means for retaining said instrument on said base, a switch operable between a plurality of positions, means connecting said switch in circuit with said circuit controlling means, and operating means for said switch po-

sitioned for movement through a path normally occupied by said securing means, said operating means being biased for movement into said path to operate said switch in response to removal of said securing means from said path.

6. In a relay unit, a detachable relay having circuit controlling means, a base for detachably receiving said relay, a lock-controlled bolt for normally preventing removal of said relay from its base, a lock-controlled switch having a normal operating position, means for operating said bolt and said switch, said means being operable to move said bolt for releasing said relay only when said switch is actuated away from said normal operating position, and means connecting said switch in circuit with said circuit controlling means for controlling a circuit.

7. In an instrument assembly, a detachable relay instrument having circuit controlling contact means subject to operation by shock, a base for detachably receiving said instrument, a switch having a movable actuating element on said base, means electrically connecting said switch to said contact means for controlling the circuit controlling effectiveness of said contact means, and a fastening element extending between said instrument and said actuating element, said fastening element including means for actuating said switch to render said contact means ineffective prior to the release of said instrument by said fastening element, said actuating means being operable for urging said instrument towards said base.

8. In an instrument assembly, a detachable relay instrument having circuit controlling contact means subject to operation by shock, a base for detachably receiving said instrument, a switch having a movable actuating element on said base, means electrically connecting said switch to said contact means for controlling the circuit controlling effectiveness of said contact means, and a fastening element extending between said instrument and said actuating element, said fastening element including means for actuating said switch to render said contact means ineffective prior to the release of said instrument by said fastening element, and said actuating means being operable for urging said instrument away from said base.

9. In a protective device, a detachable relay having circuit controlling means, a base for detachably receiving said relay, cooperating detachable contact means on said relay and said base, means including a current transformer for energizing said relay through said contact means, a trip circuit for operation by the circuit controlling means of said relay, means for opening said trip circuit, means for securing said relay against substantial detachment from said base until said trip circuit opening means is actuated to a predetermined condition, and means responsive to detachment of said relay for establishing an auxiliary electrical circuit for said transformer.

10. In an electrical relay assembly, an electrical circuit, first electrical contact means associated with said electrical circuit, second electrical contact means associated with said electrical circuit, said first and second electrical contact means being actuatable into and out of operative relationship relative to each other for changing the condition of said electrical circuit, a base, a relay unit detachably mounted on said base and having contact means for controlling said electrical circuit, means connecting the contact means of

said relay unit in circuit with said first and second contact means for jointly controlling said electrical circuit, and means permitting substantial movement of said relay unit from said base only after said first and second contact means have been actuated out of operative relationship relative to each other.

11. In an electrical relay assembly, a detachable electrical relay having circuit controlling means, a base for detachably receiving said relay, first contact means carried by said base, second contact means carried by said relay, movable means movable from a first position in the path of detachment of said electrical relay when said electrical relay is in operative position on said 15

base to a position clear of said path of detachment, electrical connecting means responsive to movement of said movable means for establishing an electrical connection between said first and second contact means only when said movable means is substantially in said first position, and means connecting said circuit controlling means in a circuit with said contact means wherein the establishment of said electrical connection controls the effectiveness of said circuit controlling means.

CHARLES P. WEST.
